FIG. 1.

FIG. 2

INVENTOR.
William C. Kitt
By John W. Strehli
ATTORNEY.

UNITED STATES PATENT OFFICE.

WILLIAM C. KITT, OF CINCINNATI, OHIO.

DESIGN FOR A BOX.

53,506.

Specification for Design.

Patented July 8, 1919.

Application filed February 14, 1919. Serial No. 277,111. Term of patent 14 years.

To all whom it may concern:

Be it known that I, WILLIAM C. KITT, a citizen of the United States of America, and a resident of the city of Cincinnati, in the county of Hamilton and State of Ohio, have invented a new, original, and ornamental Design for Boxes, of which the following is a specification, reference being had to the accompanying drawing, forming part thereof.

Fig. 2 is an isometric view of a box showing my new design.

I claim:

The ornamental design for a box, as shown.

Witness my hand at the city of Cincinnati, in the county of Hamilton and State of Ohio, this 12th day of February, 1919.

WILLIAM C. KITT.
